Primary Examiner — Brett Miller*Assistant Examiner* — Jessica M Gebhart*(74) Attorney, Agent, or Firm* — Ian B. Oglesby(57) **CLAIM**

The ornamental design for a toolbox, as shown and described.

DESCRIPTION

FIG. 1 is a front-right-top perspective view of a toolbox showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the toolbox that form no part of the claimed design.
